COMBINED DECANTER AND PUMP

Harold Levy, Kensington, N.Y.
(59 Nassau Drive, Great Neck, N.Y.)

Filed Sept. 1, 1964, Ser. No. 81,555

Term of patent 7 years

(Cl. D44—21)

FIG.1

FIG.4

FIG. 1 is a top plan view of my combined decanter and pump, showing my new design;

FIGS. 2, 3 and 4 are side elevational views of the combined decanter and pump, taken 120° apart, to show the entire outside of the article.

The body of the combined decanter and pump is circular in cross-section.

This application is a continuation-in-part of my earlier application, Ser. No. D. 73,383 of January 30, 1963 and now abandoned.

I claim:

The ornamental design for a combined decanter and pump, as shown and described.
